GEORGE T. JOHNSON AND HARRY W. STERTZBACH, OF COLUMBUS, OHIO, ASSIGNEES
TO THE BUCKEYE STEEL CASTINGS COMPANY, OF COLUMBUS, OHIO.

TRUCK SIDE FRAME.

1,378,794.

Specification of Letters Patent. Patented May 17, 1921.

Application filed July 17, 1920. Serial No. 397,094.

To all whom it may concern:

Be it known that we, GEORGE T. JOHNSON and HARRY W. STERTZBACH, citizens of the United States, and residents of Columbus, 5 in the county of Franklin and State of Ohio, have invented certain new and useful Improvements in Truck Side Frames; and we do hereby declare the following to be a full, clear, and exact description of the invention, such as will enable others skilled in the art to which it appertains to make and use the same.

This invention relates to improvements in truck side frames, and more particularly 15 to that type in which such frame is cast in a single integral structure,—one object of the invention being to so construct the side frame that the stresses will be carried up into the top portion of the extensions to 20 which the journal boxes are secured, and to eliminate the complicated coring of non-uniform sections around the journal box bolt holes as has been encountered in the manufacture of side frames as heretofore 25 constructed.

A further object is to provide the truck frame with a tie bar bracket construction, which shall be neat in appearance as well as substantial, and to so form said bracket 30 as to eliminate many of the non-uniform sections of metal heretofore occurring at this part of a truck side frame.

With these and other objects in view, the invention consists in certain novel features 35 of construction and combinations of parts as hereinafter set forth and pointed out in the claims.

In the accompanying drawings; Figure 1 is a view partly in side elevation and partly 40 in section; Fig. 2 is a bottom plan view; Fig. 3 is a partial top plan view; Fig. 4 is a section on the line 4—4 of Fig. 1; Fig. 5 is a section on the line 5—5 of Fig. 1; Fig. 6 is a section on the line 6—6 of Fig. 1, and 45 Fig. 7 is a partial end view showing the tie-bar bracket construction.

The truck side frame is of the arch type made in a single casting, and comprises a top member 1, a bottom tension member 2 and diagonal tension members 3, 3,—the latter being so united at their upper ends with the top member 1 as to provide extensions 4.

The extensions 4 are made hollow (as 55 shown in Fig. 5), having a curved top por-

tion 5, side walls 6 and a bottom 7 against which the journal box (not shown) is to be seated. The top 5 and bottom 7 of each extension are provided with openings 8 and 9 respectively for the accommodation of the 60 inside journal box bolts and the said top and bottom portions of each extension 4 are also provided (near the free end of the latter) with alined openings 10—11 for the accommodation of the outer journal box 65 bolts.

Each diagonal tension member is made with a transverse plate or web portion 12 so that a section on the line 4—4 of Fig. 1 will present the shape, approximately, of the 70 letter "H" as shown in Fig. 4. The plate or web 12 is disposed diagonally with relation to the longitudinal axis of the diagonal tension 3 and at its upper portion, said web or plate intersects the inner bolt opening 9 in 75 the bottom or base portion 7 of the extension 4. The upper portion of the plate or web 12 is provided, within the hollow extension 4 and above the bolt opening 9, with an annular boss or enlargement 13, the latter 80 being in alinement with the openings 8—9 for the accommodation of the inner journal box bolt. Ribs 14 are formed integral with and project inwardly from the side walls 6 of the hollow extension 4,—said ribs extending from the annular boss 13 to the curved top wall 5 of the extension 4 and integral with both. The ribs 14 thus form, in effect, extensions of the diagonal plate or web 12 and hence the stresses will be carried to the top of the extensions of the top truck frame member 1. By so disposing the diagonal plate or web 12 of the diagonal tension member 3 that said plate or web 85 will intersect the inner bolt opening 9, we 90 are enabled to obtain a large radius at X, and at the same time eliminate the complicated coring and the non-uniform sections around the journal box bolt holes incident to prior constructions.

It will be observed that each diagonal tension member having the form hereinbefore described runs into the full channel section as it approaches the extension 4 and into the full channel section inverted as it 105 approaches the juncture of the diagonal tension member 3 with the bottom tension member 2.

The bottom plate 15 of the bottom tension member is continued (at each end) up- 110

wardly to form portions of the diagonal tension members 3, and then made to project outwardly from the latter to provide a horizontal bracket or shelf 16 as a continuation of said bottom plate, adapted for the reception of the usual tie bar 17. Each bracket or shelf is provided with a strengthening rib 18 integral therewith and with the plate 15 and said bracket may be further strengthened by uniting it with the diagonal tension member 3 by extending the flanges of the channel section as at 19 and if further bracing is necessary, the beading on the flanges at 19 may be broadened. The bracket construction as above described permits the elimination of many of the non-uniform sections of metal which have occurred at the corresponding parts of prior constructions, and by making the bracket as a continuation of the lower plate 15 of the tension member, a large radius at X may be provided.

Having fully described our invention what we claim as new and desire to secure by Letters-Patent, is:—

1. A truck side frame having extensions from the juncture of the diagonal tension members with the top member, each diagonal tension member having a plate or web diagonally disposed relatively thereto and having a vertical bolt opening near its upper end, and each of said extensions having inwardly projecting ribs integral at one end with said plate or web and at the other end with the top of said extension.

2. A truck side frame comprising a top member, a bottom member, diagonal tension members, and hollow extensions projecting from the juncture of the top member and diagonal tension members, each extension having a bolt opening in its base portion, each diagonal tension member having a plate or web intersecting said bolt opening and provided with an annular boss alining with said bolt opening, the side wall of each extension having ribs extending from said boss to the top of the extension.

3. A truck side frame comprising top and bottom members, diagonal tension members, and hollow extensions projecting from the junctures of the diagonal tension members with the top member, each extension having

a bolt opening at its base adjacent to the juncture of the latter with a diagonal tension member, a plate forming part of each diagonal tension member and disposed diagonally with respect to the latter, said plate or web intersecting said bolt opening and provided with an annular boss alining with the latter, and ribs in each extension, said ribs extending from said boss to the top of the extension.

4. A truck side frame comprising a top member, diagonal tension members and a bottom plate for the same, said bottom plate having terminal portions at respective ends forming tie-bar brackets.

5. A truck side frame comprising a top member, diagonal tension members and a bottom plate for the same, said bottom plate having terminal portions at respective ends forming tie-bar brackets, and extensions of portions of the diagonal tension members constituting bracing means for said brackets.

6. A truck side frame comprising a top member and bottom member and diagonal tension members, said bottom member having terminal portions at its respective ends forming tie-bar brackets, flanges of the diagonal tension members being extended and uniting the latter with said brackets.

7. A truck side frame comprising a top member having extensions for connection of journal boxes, a bottom tension member and diagonal tension members, said diagonal tension members including plates or webs diagonally disposed relatively thereto, the upper ends of said diagonal tension members running into the full channel sections as they approach said extensions, and running into the full channel sections as they approach the juncture of said diagonal tension members with the bottom tension member.

In testimony whereof, we have signed this specification in the presence of two subscribing witnesses.

GEORGE T. JOHNSON.
HARRY W. STERTZBACH.
